PRISMATIC RELIGIOUS DECORATION

Alex Sanchez, 9020 Diana Drive, El Paso, Tex.

Filed June 13, 1962, Ser. No. 70,529

Term of patent 14 years

(Cl. D29—23)

FIG. 1.

FIG. 2.

FIG. 4.

FIG. 3.

FIG. 5.

FIG. 6.

FIG. 7.

FIG. 8.

FIG. 1 is a perspective view of a prismatic religious decoration incorporating my new design;

FIG. 2 is an elevation thereof rotated 60° clockwise from the position of FIG. 1 and looking through one of the three flat faces of the prism;

FIG. 3 is an elevation thereof rotated 180° counter-clockwise from the position of FIG. 1 looking through another of the three flat faces;

FIG. 4 is an elevation thereof rotated 60° counter-clockwise from the position of FIG. 1 looking through another of the three flat faces;

FIG. 5 is an elevation thereof rotated 120° counter-clockwise from the position of FIG. 1 looking at the carved edge;

FIG. 6 is an elevation thereof corresponding to the position of FIG. 1 and looking at the carved edge;

FIG. 7 is an elevation thereof rotated 120° clockwise from the position of FIG. 1 and looking at the carved edge; and

FIG. 8 is a top plan of the prismatic religious decoration.

I claim:

The ornamental design for a prismatic religious decoration, as shown and described.
